(57) **CLAIM**

The ornamental design for an electronic hookah head, as
shown and described.

DESCRIPTION

FIG. 1 is a perspective view of an electronic hookah head
showing a new design;

FIG. 2 is a left side elevation view of FIG. 1;

FIG. 3 is a right side elevation view of FIG. 1;

FIG. 4 is a top plan view of FIG. 1; and,

FIG. 5 is a bottom plan view of FIG. 1.

The broken lines are included for the purpose of showing
portions of the electronic hookah head that form no part of the
claimed design.
